FIG. 17

UNITED STATES PATENT OFFICE

2,542,919

RIGID TYPE SHEET MATERIAL AWNING

Dewey J. Freeman, Houma, La., assignor of eighty-five per cent to Lionel Babin and fifteen per cent to Dudley Melaneon, both of Houma, La.

Application June 13, 1946, Serial No. 676,457

14 Claims. (Cl. 20—57.5)

1

This invention relates to awnings such as are primarily used exteriorly on buildings and in connection with windows, porches and the like and has reference in particular to a rigid type awning construction characterized by a fixedly mounted attaching and supporting frame and a covering therefor, the latter constructed from substantially rigid sheet material such as for instance sheet metal or appropriate plastic materials.

More specifically, the invention comprehends the provision of a rigid type ventilated awning wherein the covering or roof of the awning is fashioned from prefabricated complemental members corelated and assembled to provide an outwardly and downwardly inclined roof with vertically disposed ends, said roof and ends being constructed and arranged to provide proper shedding of snow or rain and permitting effective ventilation through the material of the awning.

A meritorious feature of the invention resides in the provision of a rigid awning structure in which all of the parts and members which constitute the frame and the roof and ends are such as to enable the same to be assembled in a piece-by-piece manner and to be interconnected in such a manner as to obviate the necessity of employing screws and equivalent fasteners for securing the various members together. Thus, after a supporting frame has been mounted upon the supporting surface, such as the vertical wall of a building or the like, the complemental members forming the roof and sides of the awning may be quickly and progressively assembled. This method of assembly and the structure permitting the same thus facilitates the assembly and installation of comparatively large awnings and permits their assembly and erection on buildings from the top of ladders or scaffolds instead of necessitating their assembly upon the ground and being thereafter carried up the ladder or scaffold and hung as a unit.

Another feature of the invention resides in the provision of a simple supporting frame, in conjunction with a complemental flashing, a roof and side members for the frame, which substantially encloses the same, and wherein the insertable and removable members making up the roof are detachably connectible with the flashing for anchorage and maintenance at their upper ends, and being slidably keyed to each other and upon the frame by properly arranged and constructed keying clips.

A very important object of the invention is to provide an improved fastener in the form of a keying clip for rigidly but removably securing

2

complemental panels of channel-shaped configuration together to form a rigid roof for ventilated metal awnings; which key is so shaped as to enable the same to be retained in the complemental panels and wherein the key is adapted for adjustable attachment to the supporting framework for securing the panels thereto.

These, together with various ancillary features and objects of the invention, which will later become apparent as the following description proceeds, are attained by the present invention, preferred embodiments of which have been illustrated, by way of example only, in the accompanying drawings, wherein:

Figure 1 is a front elevational view of an awning incorporating therein the principles of this invention;

Figure 2 is an end elevational view of the same; Figure 3 is a vertical longitudinal sectional view taken substantially upon the plane indicated by the section line 3—3 of Figure 1;

Figure 4 is an elevational view of the embodiment of Figure 1, taken from the rear thereof;

Figure 5 is a vertical transverse sectional detail view taken upon an enlarged scale substantially upon the plane indicated by the section line 5—5 of Figure 1, parts being broken away;

Figure 6 is a fragmentary perspective view illustrating certain details of the fastening clip construction on the gutter members;

Figure 7 is a horizontal sectional detail view taken substantially upon the plane indicated by the section line 7—7 of Figure 1;

Figure 8 is a perspective view of the supporting frame of the awning, the roof panel and ends being removed therefrom;

Figure 9 is a vertical transverse sectional view taken substantially on the plane indicated by the section line 9—9 of Figure 3;

Figure 10 is a vertical longitudinal sectional view taken substantially upon the plane indicated by the section line 10—10 of Figure 4 and line 10—10 of Figure 9;

Figure 11 is a vertical transverse sectional detail view taken substantially upon the plane indicated by the section line 11—11 of Figure 2;

Figure 12 is a vertical longitudinal sectional detail view taken substantially upon the plane indicated by the section line 12—12 of Figure 1;

Figure 13 is a vertical transverse sectional detail view of the modified interlocking connection and seam between a modified form of side member of the awning and a louver of the same;

Figure 14 is a view similar to Figure 13 but showing the parts in their assembled relation;

Figure 15 is a vertical sectional view through the keying clip forming an essential part of the invention, taken substantially upon the plane indicated by the section line 15—15 of Figure 5;

Figure 16 is a perspective detail view showing a modified construction of the apron or skirt end of one of the roof members; and

Figure 17 is a perspective view of one of the key members.

Referring now more specifically to the accompanying drawings, wherein like numerals designate similar parts throughout the various views, attention is directed first to Figure 8 wherein the numeral 19 designates generally the supporting frame of the awning. This frame includes a pair of duplicate, horizontally disposed frame elements 20 of suitable material which are provided at their inner ends with apertured attaching ears 21 adapted to be secured to the wall or other supporting surface, as suggested in Figures 2 and 3. The elements 20 are further provided with outstanding lateral flanges longitudinally notched in saw-tooth fashion to provide lugs 22 having inclined louver-supporting and canting edges 23.

The upper portion of the supporting frame includes a flashing 24, the details of which are shown in Figure 12 and hereinafter are more fully described. The flashing is secured to the building wall or other supporting surface W, see Figures 2, 3 and 12, in a rigid but readily attached or removed manner as set forth hereinafter.

The flashing is disposed in a horizontal position and spans the upper adjacent end portions of the downwardly and outwardly inclined frame elements 25. The latter are angle shaped in cross section, see Figures 5 and 11, and have their lower ends secured suitably to the outer end portions of said horizontal frame elements 20. The inturned flanges 26 upon the members 25 terminate in apertured ears 27, corresponding to the ears 21 and being similarly secured, as in Figure 3, to the wall W.

The remaining part of the frame comprises a cross-piece or stringer 28, which is secured at its opposite outer ends to the lower end portions of the inclined frame elements 25 and is channel-shaped in cross-section as shown in Figure 15. The stringer is provided at longitudinally spaced points with detachable fasteners in the form of key members 29 of generally T-shaped configuration. These key members, also referred to hereinafter as clips, may be integral with the stringer but are usually separable, each having a grip portion 30 attached to one flange of the stringer as shown in Figures 5 and 15.

From the supporting framework of the awning is mounted the roof construction and the end panels to provide a canopy-like enclosure adapted to shed water from the same. The roof construction consists of first and second sets of panels, constituting, respectively, caps or shields and drainage gutters. The panels of each set are disposed in laterally spaced relation with the panels of the two sets being staggered or overlapping with respect to each other. The so-called gutter members, that is, the panels of the second set, except for the two end panels are designated by the numerals 32 and are channel-shaped in cross-section having a flat elongated body portion with longitudinal walls extending along the edges of the same which define longitudinal channels. The body portion or bottom wall of the panels 32 are indicated by the numeral 33, while the longitudinal walls are shown at 34. The central body portion or bottom wall 33 serves as a drainage

surface and the upstanding walls or marginal edges 34 thereof provide side walls. It is to be noted that the walls 34 are disposed in parallelism and together with the central body portion or bottom wall 33 define longitudinal channels acting as gutters to receive and discharge water or the like falling upon the awning.

The walls 34 are fashioned with lateral in-turned flanges 35. At their lower ends, the panels 32 are bent downwardly as shown to provide end portions 36, see Figure 6, particularly, which constitute apron or skirt portions.

L-shaped detents, indicated at 37, are riveted to the longitudinal walls 34 and have bendable detents or fingers 38.

The upper or inner ends of the panels 32 are provided with a slip joint connection with coacting portions of the flashing 24. As shown in Figure 12, the walls 34 at their upper ends have clearance notches 39 associated with interlocking tongues 40. The tongues, in turn, are provided with bends constituting assembling and retention beads 41.

The beaded tongues slip into the keeper seam 42 provided by a bent under flange 43 upon the flashing 24, this flange being constituted by a return bend 44 of the principal flange 45. Thus, the keeper seam 42 is substantially U-shaped in cross-section and is provided with a seat 46 to accommodate the beads 41 and has an inbent terminal 47 to provide a stop shoulder for engaging and retaining the beads in the keeper seam.

The horizontally extending central portion 48 of the flashing is fastened, as at 49, to the wall W.

The flashing 24 further provides a companion top flange 50 having a return bend 51 providing a flange 52 which constitutes part of the upper seam 53. The terminal 54 also constitutes a stop shoulder for receiving and retaining the retention bead 55 provided on the interlocking tongue 56 on the adjacent upper end portion of the panel of the first set or cap member 57.

The panels 57 are of identical construction with the panels 32 except that they are inverted and are adapted to function as caps or shields for the adjacent walls 34 and spaces between the set of panels 32.

The upper, overlying panels 57 of the first set 50 include side walls 58 which depend from the elongated body portions of these panels, and define therewith channel members. The bottom edges of the side walls 58 are in turn provided with in-turned portions to provide lateral flanges 59. The side walls are notched, as at 60, to constitute the slip joint connection between the top panels 57 and the flashing 24.

Any suitable caulking compound, as indicated at 61, may be provided for waterproofing the space between the flashing and the wall W.

The slip joint seam connection between the bottom panels 32 and the flashing 24 provides an essential means for assembling and holding the members 32 in place on the frame structure. The above mentioned key members 29 serve to partly maintain the cap or upper panels 57 upon the frame structure and the slip joint and seam connection at the top further assist. Thus, the cap sections are held in place at their upper ends and also at their lower ends, the upper ends being attached to the flashing and the lower ends to the frame. The detents 38 are utilized for purposes of interlocking the panels 32 and 57 to each other.

When the members 32 and 57 are brought to-

gether in assembled roof forming relationship, as shown in Figure 7, the tongues 38 are then bent out and clenched tightly against the side walls 58 of the upper panels 57, properly securing all of the members upon the frame. In order to remove the cap or upper member 57, it is necessary to release the detents 38 by bending the same from the full line position shown in Figure 7 to the dotted line positions shown in Figure 6. It will be noted that the outer lower bent ends 62 of the top panels coat with the bent ends 36 of the lower panels to form the skirt or apron arrangement of the awning brought out in Figures 1-3.

Referring now more specifically to Figure 17 and also to Figure 5, it will be observed that the T-shaped key members 29 are constructed from plate or sheet material and have a stem 31 of a width equal to the spacing between adjacent panels 32. From its upper portion, the stem 31 has laterally extending arm portions 31a from opposite sides of the same, which, upon their under surfaces, are recessed or cut away in the form of a vertical notch 31b where they join the stem portion. Thus, a pair of grooves, notches or channels is provided in the under surface of the arm portions of the key members. These grooves or notches serve to receive and embrace the laterally inturned flanges 35 at the upper ends of the side walls 34 of adjacent panels 32. Thus, as shown in Figure 5, the stem 31 spaces the adjacent side walls 34 of adjacent panels 32, while the inverted upper set of panels 57 embrace the lateral portions or arms 31a, the latter thus serving to space both vertically and laterally the two sets of panels. Moreover, it will be seen that the inwardly turned flanges 59, at the lower ends of the upper set of panels, underlie and engage the under surface of the lateral arm portions 31a to establish a secure seating engagement therewith, thereby preventing relative vertical movement between the upper and lower sets of panels while permitting relative sliding movement therebetween.

It will be further noted that the upper edges of the lateral arm portions 31a are bevelled or inclined, as at 31c.

The previously mentioned grip portion 30 of the key members consists of parallel portions 30a and 30b which are adapted to embrace therebetween a flange of the cross-piece or stringer 28.

All of the upper panels 57 are of the same construction as the lower panels 32. However, the two end panels of the lower panels, indicated at 32a, instead of having parallel gutter-forming side walls on opposite longitudinal edges thereof, have their outer edges depending to form edging flanges 63.

Attention is now directed to the vertical end walls completing the covering of the awning frame. These end walls comprise slats of sheet metal or louvers, which are denoted by the numeral 64, see Figure 9, each louver having laterally disposed, vertically extending reinforcing beads 65 upon opposite edges of the same. The interior sides of the louvers are provided with suitably constructed keepers or grips 66 which frictionally and releasably engage the assembling and canting lugs 22.

Inclined edges 23 on the lugs 22 serve to tilt or cant the louvers so that the respective louvers are spaced apart at proper angles for effectively shedding rain and snow, but at the same time permitting effective ventilation. The upper ends of the louvers, directly beneath the roof, are bent

at proper angles and are transversely and obliquely cut, as indicated at 67, these ends having beads 68 which serve as detents to fit into clamping and assembling seams, as shown in Figure 11. The seam is generally denoted by the numeral 69, terminating in an abutment or stop shoulder for the beads 68. As shown in Figure 11, the adjacent, upper portion of the frame elements 25 are bent at suitable angles to properly position the seam 69 to permit this separable, interlocking connection between the upper ends of the louvers and the frame structure. The louvers are thus assembled on the frame and end portions of the roof overhang the separable seam connections to suitably complete the structure.

In practice, the end bottom panels 32a in Figure 5 are slipped into place and secured by the tongue 40 in the keeper seam 42 along the lower or under side portion of the flashing, the member resting transversely on the stringer 28. The next adjacent upper or cap panel 57 is slipped into place endwise onto one of the keys and is interlocked with the key member to the stringer. This causes the adjacent longitudinal edge portions of the respective members to overlap as shown to the left in Figure 5, this overlapping serving to provide the desired degree in the overhanging, thereby promoting effective ventilation in the roof structure, while at the same time insuring proper water drainage. The tongue on the upper end of the top panel 57 is releasably fastened in the seam in the upper portion of the flashing 24.

In assembling the awning, the supporting framework is suitably assembled and erected or installed upon a building, and the key members are attached to the stringer or cross member 48. At this time, the flashing unit is attached to the building in proper place, as suggested in Figures 8 and 12. The upper and lower sets of panels are then slid upwardly from the lower end of the supporting framework, the appropriate channel members being longitudinally, slidably engaged with the corresponding portions of the key members, until the tongue and groove connections of the upper ends of these channel members are secured in the corresponding sockets or seams of the flashing unit. At this time, it will be seen that the panels are retained by their tongue and groove connection against withdrawal; while the key members serve to properly space the panels relative to each other and to fasten them to the stringer.

When the members have been progressively assembled, as set forth above, a screwdriver or the like may be inserted endwise into the depending portions 36 and 62 of the panels 32 and 57 and the retaining tongues or detents 38 may then be bent against the side walls of the upper panels to fasten the same frictionally in place, as shown in Figure 6. It will be apparent, therefore, that the bottom panels 32 simply rest upon the cross-piece or stringer 28 with their upper ends in quick, detachable interconnection with the lower seam of the flashing, while the top panels are fastened to the upper seam of the flashing at their upper ends and are secured at their lower ends to the stringer 28 and to the lower panels by the key members, the tongues or detents 38 completing the interlocking action.

The slats or louvers 64 on the ends of the awning have their upper, latterly deflected ends, as shown in Figure 11, fastened by being connected with the seam 69. The clips 66 on the lower end portions embrace and are fastened upon the inclined edge portions 23 of the outstanding lugs

as shown in Figures 9 and 10. It is evident, therefore, that the louvers, as well as the roof can be put in place one element at a time after the frame is nailed or otherwise secured to the wall.

Figure 16 shows a modified form of detent means on the bottom panels 32 for coaction with the top panels. Thus, integral detent fingers or clips 38a are struck out from the side walls 34 instead of providing separate clips riveted to the side walls, as set forth in connection with the previous embodiment. Otherwise, the construction and operation of this form of detent is identical with that previously described.

As shown in Figure 15, the key members 29 have their parallel portions 30a and 30b of the grip portion 30 slidably embracing the upper horizontal flange of the cross-piece or stringer 28, whereby the key members may be adjustably positioned longitudinally of the stringer.

As shown in Figures 13 and 14, a modified construction is provided for detachably securing the louvers to the frame elements. Thus, the frame elements 25a, having horizontal bottom flanges 26a, have their upper ends angularly disposed and inturned, as at 71, to receive the retaining elements 72 laterally bent from the upper deflected end portions 73 of a modified louver 74.

I claim:

1. A ventilated awning construction comprising first and second sets of panels, each panel having an elongated body portion with longitudinal walls defining longitudinal channels with said body portion, the walls having lateral flanges overlying said body portion, key members detachably securing said sets of panels together in spaced relation, the panels of the first set overlying the panels of the second set, the adjacent edges of the body portions of overlying panels being spaced both laterally and vertically, each key member having its upper portion extending above the walls of the panels of the second set and being of less length than said channels to provide air flow passages between said panels and having a stem positioned between and spacing the adjacent walls of panels of said second set, said stem having lateral portions overhanging said adjacent walls and received in the channels and engaging the walls and flanges of panels of the first set to prevent lateral and vertical displacement of said panels.

2. A ventilated awning construction comprising first and second sets of panels, each panel having an elongated body portion with longitudinal walls defining longitudinal channels with said body portion, the walls having lateral flanges overlying said body portion, key members detachably securing said sets of panels together in spaced relation, the panels of the first set overlying the panels of the second set, the adjacent edges of the body portions of overlying panels being spaced both laterally and vertically, each key member having its upper portion extending above the walls of the panels of the second set and being of less length than said channels to provide air flow passages between said panels and having a stem positioned between and spacing the adjacent walls of panels of said second set, said stem having lateral portions overhanging said adjacent walls and received in the channels and engaging the walls and flanges of panels of the first set to prevent lateral and vertical displacement of said panels, said awning including a cross-bar extending transversely of said panels, fastening means securing said stem of each key member to said cross-bar.

3. A ventilated awning construction comprising first and second sets of panels, each panel having an elongated body portion with longitudinal walls defining longitudinal channels with said body portion, the walls having lateral flanges overlying said body portion, key members detachably securing said sets of panels together in spaced relation, the panels of the first set overlying the panels of the second set, the adjacent edges of the body portions of overlying panels being spaced both laterally and vertically, each key member having its upper portion extending above the walls of the panels of the second set and being of less length than said channels to provide air flow passages between said panels and having a stem positioned between and spacing the adjacent walls of panels of said second set, said stem having lateral portions overhanging said adjacent walls and received in the channels and engaging the walls and flanges of panels of the first set to prevent lateral and vertical displacement of said panels, the lower surface of said lateral portions being notched to receive the lateral flanges on the second set of panels.

4. A ventilated awning construction comprising first and second sets of panels, each panel having an elongated body portion with longitudinal walls defining longitudinal channels with said body portion, the walls having lateral flanges overlying said body portion, key members detachably securing said sets of panels together in spaced relation, the panels of the first set overlying the panels of the second set, the adjacent edges of the body portions of overlying panels being spaced both laterally and vertically, each key member having its upper portion extending above the walls of the panels of the second set and being of less length than said channels to provide air flow passages between said panels and having a stem positioned between and spacing the adjacent walls of panels of said second set, said stem having lateral portions overhanging said adjacent walls and received in the channels and engaging the walls and flanges of panels of the first set to prevent lateral and vertical displacement of said panels, the lateral flanges on the upper set of panels being engaged beneath the lower surface of said lateral portions.

5. A ventilated awning construction comprising first and second sets of panels, each panel having an elongated body portion with longitudinal walls defining longitudinal channels with said body portion, the walls having lateral flanges overlying said body portion, key members detachably securing said sets of panels together in spaced relation, the panels of the first set overlying the panels of the second set, the adjacent edges of the body portions of overlying panels being spaced both laterally and vertically, each key member having its upper portion extending above the walls of the panels of the second set and being of less length than said channels to provide air flow passages between said panels and having a stem positioned between and spacing the adjacent walls of panels of said second set, said stem having lateral portions overhanging said adjacent walls and received in the channels and engaging the walls and flanges of panels of the first set to prevent lateral and vertical displacement of said panels, the lower surface of said lateral portions being notched to receive the lateral flanges on the second set of panels, the lateral flanges on the upper set of panels being engaged beneath the lower surface of said lateral portions, the adjacent edges of the lateral flanges

of adjacent panels of said first and second sets being maintained in laterally spaced relation by said lateral portions and said notches.

6. A ventilated awning construction comprising first and second sets of panels, each panel having an elongated body portion with longitudinal walls defining longitudinal channels with said body portion, the walls having lateral flanges overlying said body portion, key members detachably securing said sets of panels together in spaced relation, the panels of the first set overlying the panels of the second set, the adjacent edges of the body portions of overlying panels being spaced both laterally and vertically, each key member having its upper portion extending above the walls of the panels of the second set and being of less length than said channels to provide air flow passages between said panels and having a stem positioned between and spacing the adjacent walls of panels of said second set, said stem having lateral portions overhanging said adjacent walls and received in the channels and engaging the walls and flanges of panels of the first set to prevent lateral and vertical displacement of said panels, the lower surface of said lateral portions being notched to receive the lateral flanges on the second set of panels, the lateral flanges on the upper set of panels being engaged beneath the lower surface of said lateral portions, the adjacent edges of the lateral flanges of adjacent panels of said first and second sets being maintained in laterally and vertically spaced relation by said lateral portions and said notches.

7. A ventilated awning construction comprising first and second sets of panels, each panel having an elongated body portion with longitudinal walls defining longitudinal channels with said body portion, the walls having lateral flanges overlying said body portion, key members detachably securing said sets of panels together in spaced relation, the panels of the first set overlying the panels of the second set, the adjacent edges of the body portions of overlying panels being spaced both laterally and vertically, each key member having its upper portion extending above the walls of the panels of the second set and being of less length than said channels to provide air flow passages between said panels and having a stem positioned between and spacing the adjacent walls of panels of said second set, said stem having lateral portions overhanging said adjacent walls and received in the channels and engaging the walls and flanges of panels of the first set to prevent lateral and vertical displacement of said panels, said lateral portions having inclined portions at their outer ends.

8. A ventilated awning construction comprising first and second sets of panels, each panel having an elongated body portion with longitudinal walls defining longitudinal channels with said body portion, the walls having lateral flanges overlying said body portion, key members detachably securing said sets of panels together in spaced relation, the panels of the first set overlying the panels of the second set, the adjacent edges of the body portions of overlying panels being spaced both laterally and vertically, each key member having its upper portion extending above the walls of the panels of the second set and being of less length than said channels to provide air flow passages between said panels and having a stem positioned between and spacing the adjacent walls of panels of said second set, said stem having lateral portions overhanging said adjacent walls and re-

ceived in the channels and engaging the walls and flanges of panels of the first set to prevent lateral and vertical displacement of said panels, said stems being of greater height than that of said walls to vertically space the sets of panels from each other.

9. A ventilated awning construction comprising first and second sets of panels, each panel having an elongated body portion with longitudinal walls defining longitudinal channels with said body portion, the walls having lateral flanges overlying said body portion, key members detachably securing said sets of panels together in spaced relation, the panels of the first set overlying the panels of the second set, the adjacent edges of the body portions of overlying panels being spaced both laterally and vertically, each key member having its upper portion extending above the walls of the panels of the second set and being of less length than said channels to provide air flow passages between said panels and having a stem positioned between and spacing the adjacent walls of panels of said second set, said stem having lateral portions overhanging said adjacent walls and received in the channels and engaging the walls and flanges of panels of the first set to prevent lateral and vertical displacement of said panels, said awning including a cross-bar extending transversely of said panels, fastening means securing said stem of each key member to said cross-bar, said fastening means being mounted on said cross-bar for sliding movement thereon.

10. A ventilated awning construction comprising first and second sets of panels, each panel having an elongated body portion with longitudinal walls defining longitudinal channels with said body portion, the walls having lateral flanges overlying said body portion, key members detachably securing said sets of panels together in spaced relation, the panels of the first set overlying the panels of the second set, the adjacent edges of the body portions of overlying panels being spaced both laterally and vertically, each key member having its upper portion extending above the walls of the panels of the second set and being of less length than said channels to provide air flow passages between said panels and having a stem positioned between and spacing the adjacent walls of panels of said second set, said stem having lateral portions overhanging said adjacent walls and received in the channels and engaging the walls and flanges of panels of the first set to prevent lateral and vertical displacement of said panels, said awning including a cross-bar having a flange, said cross-bar extending transversely of said panels, fastening means securing said stem of each key member to said cross-bar, said fastening means including a pair of parallel portions embracing the flange on said cross-bar.

11. In a rigid awning, a first and second set of elongated awning surface panels, the panels having angular walls formed on their marginal edges and the walls of the panels of the first set having lateral inwardly directed flanges, the panels of the first set being inverted and overlapping the panels of the second set, laterally extending clips on the inner surfaces of the walls of the panels of the second set, said clips being bendable for angular positioning and being seated on the flanges on the walls of the panels of the first set.

12. In a rigid awning construction, a first and second set of elongated flat awning surface panels,

11

the marginal edges of the panels having parallel side walls, the walls of the first set of panels terminating in lateral inwardly directed flanges, the panels of the first set being inverted and overlying the panels of the second set, and adjustable connecting members carried by the walls of the panels of the second set and extending inwardly therefrom and seating on the flanges on the walls of the panels of the first set.

13. The combination of claim 12, wherein said members are inwardly struck from the walls of the panels and are bendable for angular positioning with respect to the walls.

14. The combination of claim 12, wherein said members include angle clips secured at one end to the inner surface of the walls, said clips being bendable for angular positioning with respect to the walls.

DEWEY J. FREEMAN.
